CLOCK

**Paul G. Darrot, Southbury, Conn., assignor to
General Time Corporation, New York, N. Y., a
corporation of Delaware**

Application February 21, 1949, Serial No. 986

Term of patent 14 years

(Cl. D42—7)

To all whom it may concern:

Be it known that I, Paul G. Darrot, a citizen of the United States, residing at Southbury, in the county of New Haven and State of Connecticut, have invented a new, original, and ornamental Design for a Clock, of which the following is a specification, reference being had to the accompanying drawing, forming a part thereof.

Figure 1 is a perspective view of a clock, embodying my new design.

Figure 2 is a side elevational view of said clock.

Figure 3 is a front elevational view of said clock.

I claim:

The ornamental design for a clock, substantially as shown.

PAUL G. DARROT.
